(57) **CLAIM**

The ornamental design for an exhaust manifold for automotive vehicle, as shown and described.

DESCRIPTION

FIG. 1 is a front perspective view of an exhaust manifold for automotive vehicle, showing our new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a cross-sectional view thereof, taken along line 9-9 of FIG. 4;

FIG. 10 is a cross-sectional view thereof, taken along line 10-10 of FIG. 6; and,

FIG. 11 is a cross-sectional view thereof, taken along line 11-11 of FIG. 7.

The broken lines in the figures depict portions of the exhaust manifold for automotive vehicle that form no part of the claimed design.

1 Claim, 10 Drawing Sheets
